(57) **CLAIM**

The ornamental design for the set of vehicle door sill scratch guards, as shown and described.

DESCRIPTION

FIG. 1 is a perspective view of a set of vehicle door sill scratch guards, showing a first embodiment of the design in an environment of use affixed to the front and rear driver side door sills of a vehicle;

FIG. 2 is a top perspective view of the set of vehicle door sill scratch guards of FIG. 1;

FIG. 3 is a top plan view of the set of vehicle door sill scratch guards of FIG. 1;

FIG. 4 is a bottom plan view of the set of vehicle door sill scratch guards of FIG. 1;

FIG. 5 is a side elevation view of the set of vehicle door sill scratch guards of FIG. 1;

FIG. 6 is an end elevation view of the set of vehicle door sill scratch guards of FIG. 1;

FIG. 7 is a perspective view of the of the set of vehicle door sill scratch guards, showing a second embodiment of the design in an environment of use affixed to the front and rear passenger side door sills of a vehicle;

FIG. 8 is a top perspective view of the set of vehicle door sill scratch guards of FIG. 7;

FIG. 9 is a top plan view of the set of vehicle door sill scratch guards of FIG. 7;

FIG. 10 is a bottom plan view of the set of vehicle door sill scratch guards of FIG. 7;

FIG. 11 is a side elevation view of the set of vehicle door sill scratch guards of FIG. 7; and,

FIG. 12 is an end elevation view of the set of vehicle door sill scratch guards of FIG. 7.

The broken lines illustrate environmental structure that forms no part of the claimed design.

1 Claim, 12 Drawing Sheets
